(57) **CLAIM**

The ornamental design for a tracked vehicle for construction, as shown and described.

DESCRIPTION

FIG. 1 is a front elevational view of a tracked vehicle for construction showing our design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front elevational view of a second embodiment of a tracked vehicle for construction having transparent windows as illustrated;

FIG. 8 is a rear elevational view thereof;

FIG. 9 is a left side elevational view thereof;

FIG. 10 is a right side elevational view thereof;

FIG. 11 is a top plan view thereof; and,

FIG. 12 is a front elevational view of the first embodiment, the broken line showing of the boom is for illustrative purposes only and forms no part of the claimed design.
